UNITED STATES PATENT OFFICE

GEORGE D. OVERHOLTZ, OF FAIR OAKS, PENNSYLVANIA, ASSIGNOR TO MCCLINTIC MARSHALL COMPANY, OF PITTSBURGH, PENNSYLVANIA, A CORPORATION OF PENNSYLVANIA

OUTDOOR ADVERTISING BULLETIN

Application filed July 11, 1930. Serial No. 467,180.

This invention relates to outdoor advertising structures, and more particularly to bulletins, as distinguished from poster panel constructions. In bulletin structures, as is well known in the art, the structure includes removable panels designed for having portions of the advertising applied directly to the individual panels, as by painting.

In such structures, it is frequently necessary to remove the panels therefrom, and one of the main objects of the present invention is to provide a bulletin of the character whereby the panels thereof may be readily removed from and applied to the structure with a minimum of trouble and expense.

A further object of the present invention is to provide a structure embodying simple and efficient means for supporting the separable panel sections in a manner to take care of the tension and compressive strains the panels and the structure are subjected to when the parts are assembled in the desired operative positions.

Other objects of my invention are, to provide for co-operation with the cross-members of the metal supporting framing of said structures, interchangeable adjustable panel attaching means for detachably securing the panel sections to the framing; and to provide a new and improved arrangement of one of the cross-members of the framing relative to the other cross-members of the structure whereby the panel sections may be more readily positioned on the structure and removed therefrom and whereby the panel attaching means may be advantageously utilized.

In the accompanying drawings:

Fig. 1 is a front perspective view of a portion of an outdoor advertising structure, showing my invention applied thereto;

Fig. 2, a horizontal section taken on the line II-II of Fig. 1, particularly showing the panel attaching means in position;

Fig. 3, a cross section on the line III-III of Fig. 2;

Fig. 4, a detail section taken on the line IV-IV of Fig. 2;

Fig. 5, a vertical sectional view illustrating the panel attaching means in engagement

with the lower side of a panel for supporting the same;

Fig. 6, a view similar to Fig. 5, showing a spacer member for positioning the bottom cross-member away from the upright;

Fig. 7, a perspective view of the bracket member of the panel attaching means;

Fig. 8, a perspective view of the bolt member of the panel attaching means; and

Fig. 9, a perspective view of a modified form of spacer member.

Referring to the drawings, 5 designates structural angle uprights of a steel framing employed for supporting the panels 6, the molding not shown, and other parts entering into the bulletin structure.

As illustrated, and as preferred, I provide three cross-members 7, 8 and 9, preferably formed of angle bars, the top cross-member 7 and the intermediate cross-member 8 are securely attached directly against a face of the structural angle members 5 by means of bolts or their equivalents 10. The bottom cross-member 9 however is spaced a slight distance away from the faces of the uprights 5 by means of spacer members 11, preferably of channel shape.

Member 9 is attached to the uprights by means of J-bolts 12 having threaded shank portions 13 passed through openings 13a in the spacer members and openings 13b in the uprights, said bolts being provided with hooked portions 14 for engaging over a flange of the member 9, and nuts 15 on the inner ends of the threaded shanks for tightening the same. The spacer members 11 are further provided with means for engagement with the vertically depending flange of member 9, said means including headed bolts 16, nuts 17 and washers 18. Openings 19 are formed in the lower portions of the spacers through which said bolts are passed to extend below the lowermost portion of the depending flange of the member 9. Upon tightening nuts 17 the washers 18 engage and clamp the depending flange of the member 9, thereby preventing tilting of said member by means of the action of the J-bolts 12.

The foregoing construction may be adapted to accommodate a splice in the cross-mem-

ber 9 when desired, by merely retracting nut 17 on its bolt 16 a sufficient distance to permit the entrance of the double thickness of angle flange.

- 5 I have shown a modified form of spacer member 11a in Fig. 9, wherein a stamped-out portion 16a is designed to be projected away from the surface of the spacer to provide a socket or recess 20 for receiving the 70
10 depending flange of the cross-member 9, thereby securing the latter against tilting. Said spacer members 11 or 11a function to position the member 9 forwardly of the members 7 and 8 for the purpose of supporting 75
15 the panels 6 in the manner hereinafter described.

The interchangeable adjustable panel attaching means constitute an important and characteristic feature of the present invention and, as shown, include an L-shaped bracket member 21 having a laterally extending lower flange 22 at one end of the member, and a depending flange 23 at its upper end. Bracket member 21 is preferably made of 80
20 relatively thick spring metal, and is designed to embrace or partially embrace the two flanges of the respective cross-members 7, 8 and 9 when applied thereto. To this end, the angle between the embracing portions of 85
25 said bracket is slightly less than ninety degrees, thereby affording a clamping action when the bracket is snapped over the flanges of the cross-members. When applied in this manner, the members 21 are designed to be 90
30 slid along the members 7, 8 and/or 9 into the desired operative positions.

The upper embracing portion of the bracket member 21 is cut and bent to form a socket 24 thereabove and extending transversely of 95
40 the said member to receive the substantially rectangular portion 25 of an L-bolt 26. Such construction prevents rotation of the bolt 26 while positioned in the socket 24.

The shank of the bolt 26 is formed with a 100
45 shoulder or abutment 27 adapted to engage the forward face 28 of socket 24 for the purpose of securing the bolt in the bracket member. 29 designates a laterally extending head portion of the bolt 26 at right angles 105
50 to the shank thereof for entrance in an opening 30 of the panels 6, said head portion being formed with a slot 31 for receiving a tapered key 32. A depending hook portion 33 is provided at one end of the bolt to prevent 110
55 movement thereof transversely of the bracket member 21.

In addition, the bracket member is formed with an upwardly projecting tapered or V-shaped element 34 forwardly of the socket 60
60 24 and spaced therefrom, as at 35, to permit the entrance of the L-bolt 26. Said element terminates in a rearwardly extending portion 36, the upper horizontal edge of which merges with the rear tapered edge of the element in a radius α . 115
65

Referring to Figs. 1 and 5, several of the bracket members are positioned along the bottom cross-member 9 without their L-bolts 26. Panels 6 are placed thereon in such a manner that the openings 37 in the lower edges thereof are engaged by the tapered elements 34. Said openings are of such diameter, and the elements 34 are so designed as to provide a binding engagement, the weight of the panels operating to bind the edges of the openings upon the radii α of the elements. 120

By reason of the spacing of the member 9 forwardly of the members 7 and 8 as described, the rear edges of the panel 6 will engage the forward edges b of said members 7 and 8 to provide vertical alinement of the panels. 125

Bracket members 21 and their L-bolts 26 positioned on the members 7 and 8 may then be slid into operative engagement with the vertical sides of the panels as shown in Figs. 2 and 3, the head portions 29 of the bolts projecting through the alined openings 30 of said panels. The tapered keys 32 may then be positioned in the slots 31 of the head portions for drawing the panels together and into relatively tight engagement with the forward edges b of the cross-members 7 and 8. 130

The elements 34 of the bracket members 135
95 elevate the panels 6 above the cross-member 9 a sufficient distance to clear the J-bolts 12 employed in connection with the spacer members 11 or 11a (see Fig. 6).

Thus it will be seen that the panels 6 may 140
100 be assembled on the framework of the bulletin structure, and readily adjusted to the desired position thereon, the bracket members 21 permitting said panels to be slid along the cross-members 7, 8 and 9 in correct alinement. When the molding (not shown) has 145
105 been applied to the structure, the panels may be easily removed without disturbing said molding by removing the keys 32 and sliding the bracket members 21 on the members 7 and 8 out of engagement with the panels, permitting the same to be lifted off the tapered elements 34 of the bracket members on the bottom member 9 a sufficient distance 150
110 to be swung clear of the lower molding and be removed. 155

I claim:

1. In an outdoor advertising structure, the combination with a support framing including a plurality of upright members, a plurality of cross-members including a bottom cross-member secured to the uprights, spacing means interposed between the bottom cross-member and the uprights to project the bottom cross-member forwardly, a bracket detachably mounted on the bottom cross-member for mounting the base of a vertically extending panel section thereon, a vertically extending panel section having a frame formed with a base opening for co- 160
120

operation with the bracket, and means passed through the spacing members and the uprights for attaching the bottom cross-member to the uprights.

5 2. In an outdoor advertising structure, the combination with a support framing including a plurality of upright members, a plurality of cross-members including a bottom cross-member secured to the uprights, spacing means interposed between the bottom cross-member and the uprights to project the bottom cross-member forwardly, a bracket detachably mounted on the bottom cross-member having a tapered projecting element, 10 15 a vertically extending panel section having a frame formed with a base opening for cooperation with the tapered element of the bracket, and means passed through the spacing members and the uprights for attaching the bottom cross-member to the uprights.

20 3. In an outdoor advertising structure, the combination with a support framing including a plurality of upright members, a plurality of cross members including a bottom cross-member secured to the uprights, spacing means interposed between the bottom cross-member and the uprights to project the bottom cross-member forwardly, a bracket detachably mounted on the bottom cross-member, a bracket detachably mounted on the second cross-member, a vertically extending panel section having a frame formed with a side opening and a base opening, an element on the bracket mounted on the bottom cross-member for cooperation with the base opening of the panel section, and means cooperating with the bracket on the second cross-member and with the side opening of the panel section frame.

25 30 35 40 45 In testimony whereof I affix my signature.
GEORGE D. OVERHOLTZ.
